GUN SIGHT

Ambrose H. Evans, Hutchinson, Kans.

Application February 4, 1946, Serial No. 645,265

8 Claims. (Cl. 33—47)

1

This invention relates to gun sights designed primarily for use on rifles, shotguns, etc.

It is a fact well known to marksmen that gun sights heretofore used do not enable the marksman to draw a bead on the target as quickly and accurately as desired inasmuch as the cooperating front and rear sights generally have been so constructed that the user must first bring them carefully into line with the target. Some forms of sights are especially difficult to use in the dark and all of them as far as I am aware, have required a steady and careful movement of the sight until such time as they can be brought into line with the target.

An object of the present invention is to provide a gun sight the front and back members of which are so constructed as to enable the user to quickly draw a bead on the target without the usual difficulty in shifting the front end of the barrel until such time as the front sight is brought into line with the target and the rear sight.

It is a further object of the present invention to provide front and rear sights which cooperate to instantly form a peep-hole in line with the target, the formation of this peep-hole indicating to the user that an accurate bead on the target has been drawn.

It is another object of the invention to provide gun sights the members of which are reversible whereby luminous portions can be brought into view of the user to define the peep-hole which is created when the sights are brought in line with the target, thereby rendering the sights particularly desirable for use in the dark.

A still further object is to provide a gun sight one of the members of which has beads of contrasting colors whereby proper location of one of the members of the sight relative to the other is expedited, the contrasting shades of the exposed surfaces of the gun sight serving to aid the user in drawing a bead on the target whether the target is of a light or a dark color.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a side elevation of a portion of a

2

rifle equipped with the present improvement, the gun sight being shown in vertical longitudinal section and positioned for daytime use.

Figure 2 is a top plan view of the structure shown in Figure 1.

Figure 3 is a section on line 3—3 Figure 1.

Figure 4 is a section on line 4—4 Figure 1. Figure 5 is an elevation of the front sight, illustrating that face thereof opposite the one shown in Figure 3.

Figure 6 is an elevation of the cooperating beads as viewed by the user of the gun, the sights being positioned as shown in Figures 1 and 2 for daytime use.

Figure 7 is an enlarged section through one of the beads.

Referring to the figures by characters of reference S designates a portion of the stock of a rifle or the like and B designates a portion of the barrel.

The barrel is equipped with a rear sight member R and a front sight member F which can be attached to the barrel in any desired manner.

The rear sight member includes a supporting member 1 which can be attached to the barrel B in any suitable manner and mounted on this member is the base 2 of the rear sight. This base is mounted for lateral swinging movement on a pivot element 3 and it is provided at one end with suitable means whereby said base can be swung laterally in either direction on the member 1. This means can include a spring tongue 5 extending from the base 2 and frictionally engaging the top surface of the member 1. Notches 6 and 7 can be formed in the supporting member 1 and tongue 5 is adapted to snap into either of them. As they are diametrically opposed, the tongue will cooperate with them to hold the base 2 in either of two oppositely extended positions.

Mounted on the base 2 at that end thereof remote from the tongue 5 are spaced arms 8 the upper ends of which are extended toward each other to form fingers 9. Cylindrical beads 10 are carried by the fingers and are parallel with each other and with the longitudinal center of the barrel B. As shown particularly in Figure 7 each of these beads can have screw plugs 11 extended into the ends thereof from heads 12 and 13 which preferably are coaxial and circular. It is preferred to make the exposed flat surface of the head 12 with a luminous coating of any suitable kind whereas the exposed circular surface of the head 13 can be white or non-luminous if desired. The two beads are accurately and similarly posi-

tioned relative to the axis of the bore of the gun barrel and the space between the beads provides a narrow clearance through which the target can be viewed by the user. When the rear sight is positioned as shown in Figures 1, 2 and 4 the white heads 13 are exposed to the view of the user but obviously by reversing the position of the rear sight the luminous heads 12 will be brought into view.

The front sight, like the rear sight, has a suitable supporting member 14 carried by the barrel and pivotally mounted on this member is the base 15 of the front sight. The parts are connected by a pivot element 16. Extending upwardly from one end of the base 15 is a frame 17 extending transversely and provided with an upwardly extending arm 18 positioned beneath a depending arm 19. These arms, 18 and 19 carry lower and upper beads 20 and 21 respectively which are parallel to each other and to the longitudinal axis of the bore of the rifle. Both of the beads are equipped with caps which can be mounted as shown in Figure 7 but the front sight differs from the rear sight in that bead 20 has a luminous cap 22 at one end and a white cap 23 at its other end while bead 21 has a luminous cap 24 at one end and a dark cap 25 at its other end. For daytime use the caps 23 and 25 are exposed to the view of the user of the gun.

The two beads 20 and 21 are spaced apart to provide a clearance through which the target can be seen and these beads are so positioned relative to each other and to the beads 10 that when the rifle is fixed on the target, the beads on the two sights will define a peep hole 26. When the sights are positioned for daytime use or use in bright light, the heads 13 and 23 will expose their white surfaces while the head 25 will expose its dark surface, as shown in Figure 6. It has been found in practice that an arrangement of this kind enables the user of the firearm to quickly locate the target within the two sights so that time frequently lost in trying to bring the one sight into line with the other sight is eliminated. Furthermore by providing exposed surfaces of contrasting colors, the target can be more readily distinguished while aim is being taken whether said target is of a light shade or a dark shade.

When the firearm is to be used in the dark, it is desirable to reverse the two sights so as to bring the luminous surfaces thereof toward the user. Consequently, when proper aim is taken at a target, the luminous beads can be easily located relative to each other in order to bring them into clustered relationship as indicated for example in Figure 3.

It will be noted that the base 15 has an extension or tongue 27. This can be snapped into engagement with either of two nodes 28 diametrically disposed relative to the pivot element 16 so that the front sight thus can be held in either of two positions.

By pivotally mounting the base 2, and providing a frictional contact between the tongue 5 and the supporting member 1, the rear sight can be adjusted laterally about its pivotal connection 3 to allow for windage.

What is claimed is:

1. A gun sight including front and rear members each including a base pivotally connected intermediate its ends to a gun barrel for lateral swinging movement thereon, whereby to permit reverse positioning of each of the members, parallel elongated upper and lower spaced beads

carried by one of the members, and parallel elongated spaced side beads carried by the other member, all of the beads cooperating to define a peep-hole for exposure of the target at which the gun is aimed, the beads of one of the members being of contrasting shades of color at one end, one end of the beads of the other member corresponding with one of said shades, the remaining ends of all of the beads being luminous.

2. A gun sight including front and rear members, one of the said members including a base pivotally connectable to a gun barrel for lateral swinging movement thereon, whereby to permit reverse positioning of said base, spaced upwardly extending arms thereon, and spaced elongated beads on the arms parallel to each other and to the bore of the gun barrel and the other member including a base pivotally connectable to the barrel for lateral swinging movement thereon, whereby to permit reverse positioning on the barrel, upper and lower elongated beads spaced from each other and parallel, all of the beads cooperating to define a peep-hole when pointed at a target, and interengaging means cooperating between the respective bases and the barrel, adapted to align and retain the bases parallel with the barrel's axis after reverse positioning of said bases.

3. The combination with a gun barrel having spaced connections thereon, of a gun sight including front and rear members pivotally mounted on the connections, each of said members including a base pivotally connected to the barrel for swinging movement, on said connections, into a reversed position, and spaced parallel elongated beads on the bases, all of the beads being parallel with the bore of the barrel and with each other, all of said beads cooperating to define a peep-hole when the barrel is aimed at a target, all of the beads having luminous surfaces exposed to the user when the members are in one position and one of the members having a bead of a shade, at one end, contrasting with the shades of the corresponding ends of the other beads.

4. The combination with a gun barrel, of a gun sight including front and rear members, each member including a reversible base pivotally joined to the barrel, laterally spaced parallel elongated beads carried by one of the members, and vertically spaced parallel elongated beads carried by the other member, all of the beads cooperating to define a peep-hole to frame a target at which the barrel is aimed, all of the beads having luminous surfaces exposed to the user when the members are in one position and one of the members having a bead of a shade, at one end, contrasting with the shades of the corresponding ends of the other beads.

5. The combination with a gun barrel, of a gun sight including front and rear members each reversibly swingable on the barrel, interengaging means cooperating between each member and the barrel, adapted to align and retain the members parallel with the barrel's axis when in normal or reversed position, laterally spaced elongated beads carried by one of the members, and vertically spaced elongated beads carried by the other member, all of the beads being normally positioned parallel to the bore of the barrel and cooperating to provide a peep-hole for framing the target at which the barrel is pointed.

6. For mounting upon a gun barrel, a gun sight comprising front and rear members each including a base pivotally connectable to the bar-

2,471,027

5

rel for swinging movement in a plane substantially parallel with the barrel's axis, whereby to permit the reversing of each base, upper and lower elongated beads carried by one of the bases parallel to each other and to said base, and elongated side beads carried by the other base parallel to each other and to said other base, all of the beads cooperating to define a target-exposing peep hole.

7. For mounting upon a gun barrel, a gun sight including front and rear members each including a base pivotally connectable to the barrel for swinging movement in a plane substantially parallel with the barrel's axis, whereby to permit the reversing of each base, means for retaining each base against movement when in its normal or reversed position, upper and lower elongated beads carried by one of the bases parallel to each other and to said base, and elongated side beads carried by the other base in parallel relation to each other and to said other base, all of the beads cooperating to define a target-exposing peep hole.

8. For mounting upon a gun barrel, a gun sight including front and rear members each including a base pivotally connectable to the barrel for swinging movement in a plane substantially parallel with the barrel's axis, whereby to permit the reversing of each base, means for

6

retaining each base against movement when in its normal or reversed position, upper and lower elongated beads carried by one of the bases parallel to each other and to said base, and elongated side beads carried by the other base in parallel relation to each other and to said other base, all of the beads cooperating to define a target-exposing peep hole, the beads of one of the members being of contrasting shades of color at one end, one end of the beads of the other member corresponding with one of said shades, the remaining ends of all the beads being luminous.
